ISAAC M. WELLS, OF JEFFERSONVILLE, OHIO, ASSIGNOR TO HIMSELF AND
WILLIAM WOOD, OF THE SAME PLACE.

Letters Patent No. 65,710, dated June 11, 1867.

IMPROVED BURGLAR-ALARM.

The Schedule referred to in these Letters Patent and making part of the same.

TO WHOM IT MAY CONCERN:

Be it known that I, ISAAC M. WELLS, of Jeffersonville, Fayette county, Ohio, have invented a new and useful Burglar-Alarm; and I hereby declare the following to be a full, clear, and exact description thereof, reference being had to the accompanying drawing, making part of this specification.

This invention relates to a burglar-alarm which may communicate with many points in a building, so as to alarm the inmates should an entrance be attempted through any one of them.

In the drawing, A shows a box or frame furnishing bearings for the separate parts of the device constituting my invention. B is a post or shaft, having at its upper end a disk, B, from whose upper side project pins E, on which are slipped rings F at one end of cords G, whose outer ends being attached to windows, doors, drawers, &c., cause any opening or disturbance thereof to be followed by a strain upon said cords and a tipping of the post B. To the lower end of the post B is affixed a wheel, H, the hub I of the wheel on the lower side forming a pivot, i, which enters a suitable cavity in the top of the frame at a. Connecting with the wheel near its periphery are cords J, which, passing vertically through the top of the frame, connect with a lever, K, at staple k, so as on the drawing of the cords J, resulting from the tipping of the post B, to retract the said lever and draw the catch L from between the teeth m of the wheel M, allowing the said wheel to revolve in obedience to the pressure of the spring N through the medium of wheels O and P. In revolving the cogs m act on verge Q, causing the reciprocation of the knob R, which at each end of its stroke impinges upon the inside of bell S, which serves by its ringing to alarm not only the inmates of the house but also the burglars. It will be observed that the machine requires to be wound up like a clock-alarm of ordinary construction by the key T, represented over the square end of the shaft of wheel O. A catch, U, serves to retain the lever K in contact with the wheel M, when the machine may be wound but unset.

The breaking of the cords or any other part of the machine is insured against from a violent drawing of the cords, as the sloping position of pins E, when the alarm has been sounded, allows the rings to slip therefrom and the cord to be released.

A modification of my device may be so arranged as to release a hammer which may explode a percussion cap.

I claim herein as new, and of my invention—

1. The post or shaft B, wheel or disk H, with cords J operating to free the verge-wheel M, as and for the purpose stated.

2. In combination with the shaft B, disk H, cord J, and pivoted lever K, I claim the pin or pins E, allowing the cords G to be self-detaching when they have performed their duty of starting the alarm.

In testimony of which invention I hereunto set my hand.

ISAAC M. WELLS.
